UNITED STATES PATENT OFFICE.

ROBERT J. KEHL, OF CHICAGO, ILLINOIS, ASSIGNOR TO OXWELD ACETYLENE COMPANY, A CORPORATION OF WEST VIRGINIA.

MULTIPLE-FLAME BLOWPIPE NOZZLE.

Application filed June 11, 1931. Serial No. 476,859.

This invention relates to blowpipe nozzles and particularly to improved multiple flame nozzles adapted for use on machine welding blowpipes, but it will be understood that certain features of the invention are of more general application.

In multiple flame blowpipe nozzles, as heretofore constructed, outlet passages have been formed by "straight drilling". The tips of the flames produced by such nozzles are blunt and spread too far on both sides of the line of weld, wasting heat and gas. Generally, the gas enters a relatively large inlet cavity or passage in the nozzle and is not uniformly distributed to the series of outlet passages leading from such cavity. Furthermore, the orifices of nozzles heretofore used have been permanently open and accordingly it has usually been necessary to employ different nozzles for different classes of welding.

The principal objects of this invention are to provide an improved type of blowpipe nozzle in which the gas supplied to the nozzle will be more uniformly distributed to the outlet passages which desirably have portions tapering toward the orifices thereof, such orifices being desirably variable in their general arrangement as to size, number in use, location and relative distance from the weld.

The above and other objects and the novel features of this invention will be understood from the following description taken in connection with the accompanying drawings, in which—

Fig. 1 is a sectional view of a multiple flame blowpipe nozzle embodying the present invention, showing the same coupled to a gas supply device.

Figs. 2 and 3 are, respectively, an end elevation and a cross section on the line 4—4 of Fig. 1.

Fig. 4 is a central sectional view of another nozzle embodying the present invention,

Fig. 5 is a cross sectional view of the same taken on the line 6—6 of Fig. 4,

Figs. 6, 7 and 8 are, respectively, a top view; a vertical sectional view on the line 8—8 of Fig. 6; and a bottom view of a distributing block embodying this invention,

Figs. 9 and 10 are, respectively, a sectional view and a top view of another multiple flame nozzle embodying this invention, and

Fig. 11 is a sectional view of another multiple flame nozzle embodying this invention.

A nozzle embodying the present invention comprises a body, usually a brass, copper or bronze casting, having a main gas inlet passage constructed and arranged so as to direct and distribute the entering gas to the several entrances of a series or row of outlet passages leading from the bottom of the inlet passage. Also the outlet passages may or may not be provided with threaded portions adjacent the orifices thereof whereby suitable tips and plugs may be interchangeably coupled to the nozzle to permit the variation of the orifice arrangement in accordance with the class of work being welded.

The nozzle illustrated in Figs. 1, 2 and 3 comprises a body N, usually of brass or the like, provided at its upper end with suitable means whereby the same may be coupled to a gas-supply device such as a gas mixer M. As shown, the nozzle body has an outwardly extending flange 20 that is adapted to be engaged by a nut 21 having a screw-threaded part interfitting with a similar screw-threaded part on the gas mixer, whereby the upper inlet end of the nozzle may be clamped against and in line with the outlet of the mixer. The lower end of the nozzle N is reduced as at 22 and has a series of steps 23 on its lower side into which the orifices 24 open. The reduced part 22 also has therein a series of outlet passages 25 which taper to the orifices 24, the entrances of such tapering passages being in the bottom of an inlet passage or cavity C in the upper part 90 of the nozzle body. The cavity C may be formed by drilling parallel and intersecting passages 26, 27' and 28', as shown in Figs. 1 and 3, such passages being arranged to uniformly distribute the gas to the several outlet passages 25. The passages 25 may be drilled by suitable tapering tools inserted through the several passages of the cavity C. The flames produced with a nozzle of the type shown in Fig. 1 are tapering and may be closely confined to the line of weld, thus economically utilizing gas.

Figs. 4 to 11 inclusive illustrate nozzles employing another type of distributing means whereby the entering gas is more uniformly distributed to the several outlet passages leading from the bottom of the main gas inlet passage or cavity C. Referring to

Figs. 4 and 5, for example, the upper portion of the nozzle body N' may have a cylindrical cavity C' formed therein, the outlet passages 251 leading from the bottom of such cavity and tapering toward their orifices 241, in the stepped lower side of the nozzle. The distributing means in the inlet passage or cavity C' desirably comprises a substantially cylindrical block B of suitable metal such as brass or the like, which is suitably held in place, as by means of solder 27. Referring also to Figs. 6, 7 and 8, the distributing block B has a gas passage therethrough, the upper or inlet portion 28 of which tapers to a point intermediate the ends of the block, the lower or outlet portion 29 of the passage then flaring to the lower end of the block and to the entrances of the outlet passages 251. The passage through the distributing block B may be of any desired shape but is desirably elongated, as shown. Otherwise the nozzle shown in Figs. 4 and 5 is substantially similar to the one shown in Fig. 1, both having substantially parallel outlet passages which will produce flames disposed close together.

In the nozzles shown in Figs. 9, 10 and 11, the distributing blocks B' and B'' are substantially similar in construction and function like the one shown in Figs. 4 to 8, distributing the entering gas to the several outlet passages 252 and 253 leading from the bottoms of the cavities in the nozzle bodies N'' and N^3 . The nozzle bodies N'' and N^3 may have neck portions 30, externally threaded as shown so they may be coupled directly to a mating threaded portion of a gas-supply device, the upper part of the body being provided with a collar 31 having flattened portions 31' whereby a wrench may be applied to couple and uncouple the nozzle. The orifices 242 and 243 of the nozzles N'' and N^3 are spaced apart a greater distance than those in Figs. 1 and 4 so as to provide a flame having a greater length and heating period longitudinally of the seam. The several gas passages 252 and 253 extend through the nozzle body obliquely as well as parallel to the axis of the main inlet passages. Passages may branch from the outlet passages, as for example the passage 253' leading from the passage 253, in Fig. 11. The outlet passages may be provided with tapering portions as the passages 252' in Fig. 9, or they may be formed by "straight drilling" as the passages 253 of Fig. 11.

The lower sides of these nozzle bodies are desirably stepped as illustrated and threaded portions 32 and 33 may be provided adjacent the orifices of the outlet passages whereby suitable tips T , T' provided with mating threaded portions may be coupled directly to the nozzle bodies. These tips may be of suitable metal such as copper, brass or the like, and may be provided with passages 34 which taper to the

orifices 35 thereof, producing a row of flames in the plane of the outlet passages in the nozzle body and adapted to be closely confined to the line of weld. Since the tips of a given nozzle are readily interchangeable, the arrangement thereof may be varied as desired to provide a variation of the size, location and number of orifices as well as a variation in the distance of the orifices from the weld. Furthermore, by providing suitable threaded plugs P as illustrated, the orifices may be closed off as desired. Each nozzle may be provided with one or more sets of tips and plugs to provide a wide range of use for the nozzle.

While the improved blowpipe nozzles have been shown and described in detail, it is to be understood that various changes may be made therein without departing from the spirit of the invention or sacrificing any of its advantages.

I claim:

1. A multiple flame blowpipe nozzle having an inlet cavity, outlet passages leading from said cavity, and a gas directing means in said cavity having a central passage therethrough tapering to a point intermediate its ends and then flaring to the entrances of said outlet passages.

2. A multiple flame blowpipe nozzle comprising a body having means adjacent the inlet end thereof whereby the same may be secured to a gas-supply device, a cavity therein, a series of gas outlet passages leading from the bottom of said cavity and having portions thereof tapering toward a corresponding series of orifices in the lower side of said body, and a block in said cavity having an axial gas passage therethrough that tapers from adjacent the inlet of the body to a point above the bottom of the cavity and then flares to a point adjacent the entrances of said outlet passages in the bottom of the cavity.

3. A multiple flame blowpipe nozzle comprising a body having means whereby the same may be coupled to a gas-supply device, a row of outlet passages, and a gas inlet passage tapering to a point intermediate its ends and then flaring toward the inlet ends of said outlet passages, said outlet passages having portions tapering toward the orifices thereof.

4. A multiple flame blowpipe nozzle comprising a body having means whereby the same may be secured to a gas-supply device, said body having a stepped lower side and a series of outlet passages tapering to orifices in the several steps on said lower side, said body also having an inlet passage that tapers a portion of its length and then flares toward the entrances of said inlet passages.

5. A multiple flame blowpipe nozzle comprising a body having means whereby the same may be coupled to a gas-supply device, a series of outlet passages in said body, tips severally and removably connected to the several outlet passages and having tapering pas-

sages, and a main axial inlet passage that tapers from adjacent the inlet of the nozzle and then flares toward the entrances of said outlet passages.

5. 6. A multiple flame blowpipe nozzle comprising a body having an exteriorly threaded neck adjacent one end whereby the same may be coupled to a gas-supply device, said neck having a gas inlet cavity therein, a series of

steps on the lower side of said body, outlet 10 passages leading from the bottom of said cavity to said series of steps, said cavity having an axial passage therethrough that tapers a portion of its length and then flares toward the entrances of said outlet passages.

15 In testimony whereof, I affix my signature.

ROBERT J. KEHL.
